[57] CLAIM

The ornamental design for a three tube heat exchanger panel, as shown and described.

DESCRIPTION

FIG. 1 is a front elevational view of a three tube heat exchanger panel, showing my new design, the rear being a mirror image thereof;

FIG. 2 is a top edge elevational view of the panel as seen with respect to FIG. 1;

FIG. 3 is a bottom edge elevational view of the panel as seen with respect to FIG. 1;

FIG. 4 is a side elevational view taken from the left side of the panel as seen with respect to FIG. 1;

FIG. 5 is a side elevational view taken from the right side of the panel as seen with respect to FIG. 1;

FIG. 6 is an enlarged partial perspective view of the panel section along line 6—6 of FIG. 1;

FIG. 7 is an enlarged partial perspective view of the panel section along line 7—7 of FIG. 1.
